UNITED STATES PATENT OFFICE.

HARRY H. LABADIE AND BURTON B. BEERS, OF CHICAGO, ILLINOIS; SAID BEERS AS-
SIGNOR TO KNICKERBOCKER CASE COMPANY, OF CHICAGO, ILLINOIS, A CORPORA-
TION OF ILLINOIS.

SAMPLE CASE.

Application filed June 14, 1926. Serial No. 115,836.

This invention relates to improvements in sample cases, or similar display cases, and more particularly to an improved form of tray construction for use in such a case, whereby the sample will be more attractively displayed, more completely visible, easily accessible, and still fully protected against dirt and handling.

One object of the invention is to provide an improved tray for sample cases, the tray being open at the top and one side, so that the full height of the sample is completely visible.

Another object is to provide a sample case involving a plurality of trays, each tray being open at the top, and one side, and so connected together that when the trays are extended laterally in stepped relation to one another, the open tops and sides will form one substantially continuous exposure, thus fully displaying all of the articles in the trays.

Another object is to provide a removable tray closure, for a tray of the type hereinabove referred to, such closure embodying a continuous and unobstructed transparent cover for the open side and top of the tray.

Another object is to provide means along the open side of the tray for holding the closure, or the samples, in place within the tray.

Another object is to provide improved means for holding the samples in fixed display positions within the tray.

Other objects and advantages of this invention will be more apparent from the following detailed description of one approved form of sample case involving the principles of this invention.

In the accompanying drawings:

Fig. 1 is a perspective view of the sample case with the covers or closures opened. The left-hand stack of trays are shown in the superposed position in which they are placed when the sample case is closed. The right-hand assembly of trays is shown extended to the display position.

Fig. 2 is a perspective view of one of the improved tray closures or covers.

Fig. 3 is a plan view of one of the trays 50 with the closure in place therein.

Fig. 4 is a transverse vertical section taken substantially on the line 4—4 of Fig. 3.

Fig. 5 is a detail vertical section on an enlarged scale, taken substantially on the line 5—5 of Fig. 3.

The outer portion of the sample case, in the form here shown by way of example, is of a well-known type, built up of suitably reinforced leather, or other materials, and 60 comprises the bottom portion 1 to the sides of which are hinged the two upper halves 2 and 3, which when in opened position are adapted to be swung out and down to the positions shown in Fig. 1. When the case is 65 closed, flanges 4 at the edges of member 2 are adapted to enclose the edge portions of member 3, and the two members are adapted to be secured together by the usual fastenings indicated at 5 and 6. One or both of 70 the members 2 and 3 may be provided with a carrier handle or handles, as indicated at 7.

The tray construction comprises a large bottom tray 8 adapted to fit snugly within the bottom portion 1 of the sample case, and 75 a plurality of smaller display trays 9 which are flexibly connected with the upper open side of the main tray 8. The trays 9 may be of various depths, but each tray is preferably of substantially the same length, and 80 substantially half the width, of the main tray 8, so that the trays when in superposed position (as shown at the left of Fig. 1), will be stacked in two similar adjacent columns above the tray 8 and will fit snugly 85 within the closed sample case. The trays are preferably made of sheet aluminum, although wood, tin, or other materials may be used for this purpose. A metal strip 10 is secured along the upper edge of the end of each tray, and the strip 10 on one tray is connected with the corresponding strip 10 on the tray directly therebelow, by a pair of similar parallel metal links 11. One of these links extends from one end of the upper strip 10 to substantially the central portion of the lower strip 10, and the other link extends from the center of the upper strip

90

95

10 to the opposite end of the lower strip 10. The links 11 are pivoted at their ends to the strips 10 so that a tray may be swung from the position shown at the left of Fig. 1, 5 where it is directly superposed upon the next lower tray, to the position shown at the right of Fig. 1 where it is extended laterally in stepped relation to the lower tray. When in this latter position, a narrow edge portion 10 of the upper tray will rest upon the upper edge of the lower tray, so as to support the upper tray in this position. Each tray moves independently of every other tray, that is, all of the trays may be extended as 15 shown at the right of Fig. 1, or, for example, only the upper tray can be extended so as to display the articles in the first two trays, without disturbing the remaining trays in that stack. Obviously, the stack of trays to 20 the left of Fig. 1 will be extended toward the left, in a direction opposite to that in which the other stack of trays has been extended. The number of trays used, and the depths of the different trays, may be varied 25 as desired, this selection only being limited by the size of the case in which they are to be housed.

Each tray comprises a bottom 13, ends 14, and a vertical side 15. The tray is open at 30 the top and at the side opposite the side member 15. At the open side, the bottom 13 is bent upwardly to form a narrow vertically extending strip 16, which functions as hereinafter noted.

35 The improved closure or cover for the tray (as best shown in Figs. 2, 3, 4 and 5), consists of a metal framework 17, preferably bent up from thin sheet aluminum or similar material, and a transparent cover portion 18 which is reinforced and held in place by the metal framework. This transparent cover portion 18 is preferably formed of the material known as "film celluloid", which is thin, flexible, and very transparent, 40 but quite strong and durable. This material is bent along the open upper edge of the tray to form a continuous and unobstructed cover which extends over the top and down the open side of the tray. The ends 19 and 45 vertical side 20 of the metal framework 17 are doubled back upon themselves as indicated at 21 and 22, to grip and support the inwardly folded edge portions of the transparent sheet 18, and end and side flanges 23 and 24 are folded over at the top onto the transparent cover. The lower free edge of 50 the downwardly extending side 25 of the transparent cover is enclosed in the channel member 26, preferably formed of the same metal as the remainder of frame 17, the ends of this channel 26 being bent inwardly and secured between the members 19 and 21 as indicated at 27. It will be noted 55 that all of the free edges of the transparent covering are enclosed and reinforced by the

metallic frame, but there are no metal portions whatever, or other parts adapted to obstruct the view, along the open top and side of the closure. The closure is somewhat shorter than the inner dimension of the tray 70 9 so as to fit freely therein, but is of substantially the same width as the inner dimension of the tray and preferably the edge enclosed by channel 26 will bow outwardly somewhat as indicated in dotted lines in Fig. 3. This outward bowing will be caused by the natural resiliency of the transparent material 18 and the channel member 26. When the closure is inserted within the tray, 75 the rear wall 20 will engage against the rear wall 15 of the tray, and the bowed portion at the front will be sprung inside of the upwardly extending strip 16 along the lower edge of the open side of the tray, so that the closure will be held yieldably in 80 place.

As indicated in one of the open trays in Fig. 1, and also in Figs. 3 and 4, the samples 28 may be attached by ribbons 29, or other suitable means, to a pad or cardboard 30 which rests on the bottom 13 of the tray and fits loosely within the tray and closure. This pad serves to hold the samples in desired fixed positions, regardless of the movements 90 imparted to the trays, and carrying case. Holes 31 may be provided in the bottoms 13 of the trays, to facilitate lifting the pads and the samples carried thereby out of the trays.

95 It will be noted that when the trays are moved to the open or extended position, the entire contents of all of the trays will be exposed in one substantially continuous and unbroken view from one end of the series of trays to the other. The sides and ends of the samples, as well as the tops, will be clearly visible, and at the same time all of the samples are completely covered and protected by the transparent closures. It is intended that the samples exhibited in the 100 several trays 9 are merely for exhibition purposes and not to be handled, and loose samples for handling or consumption may 105 be carried in the larger bottom tray 8.

110 It will be apparent that the improved trays with the open sides and tops could be used without the transparent closures, and the advantage of freedom of vision would be retained, although the protection afforded by 115 the closures would be sacrificed. In such case, the pads 30 which hold the samples would be held in place as before by the closed side and ends of the tray, and the co-operating vertical strips 16.

120 While one particular form of sample-case, adapted to house two similar stacks of trays opening in opposite directions, is here shown and described by way of example, it is to be understood that the improved tray construction and transparent closure therefor could 125 130

be mounted in other types of bags or cases and arranged differently than here shown. For example, a single stack of trays might be used, or one or more independent stacks 5 could be superposed above one another in a manner heretofore well-known in this art.

We claim:

1. A sample-case tray comprising a bottom, ends, and one vertical side, the opposite 10 side and the top of the tray being substantially open and a covering of transparent material for the open side and top.

2. A sample-case tray comprising a bottom, ends, and one vertical side, the opposite 15 side and the top of the tray being substantially open and a removable covering of transparent material for the open top and side.

3. A sample-case tray comprising a bottom, ends, and one vertical side, the opposite 20 side and the top of the tray being substantially open, a narrow strip extending vertically from the bottom at the open side, and a closure for the tray comprising a framework adapted to fit within the tray 25 and a continuous covering of transparent material extending unobstructedly over the open top and side.

4. A sample-case tray comprising a bottom, ends, and one vertical side, the opposite 30 side and the top of the tray being substantially open, a narrow strip extending vertically from the bottom at the open side, and a removable cover for the tray comprising a continuous transparent covering adapted to 35 extend unobstructedly over the open top and side of the tray and a metallic framework secured to and reinforcing the free edges of the transparent covering, said framework fitting yieldably between the vertical side 40 and strip of the tray.

5. A cover for a sample-case tray, comprising a continuous sheet of transparent material forming the top and one vertical 45 side of the cover, and a metallic framework secured to the free edges of the transparent sheet, and forming the ends and other side wall of the cover.

6. A cover for a sample-case tray, comprising a continuous sheet of transparent 50 material forming the top and one vertical side of the cover, and a metallic framework formed of channel members enclosing and gripping the free edge portions of the transparent sheet, and also forming the ends and other side wall of the cover.

7. A cover for a sample-case tray, comprising a continuous sheet of transparent material forming the top and one vertical 60 side of the cover, and a metallic framework comprising a piece of sheet material bent to form the ends and other vertical side of the cover and doubled back in channel formation to enclose and grip the adjacent inturned edges of the transparent sheet, and a narrow 65 metallic channel reinforcing the lower edge

of the transparent side wall, the ends of this channel being secured to the metallic end walls of the cover.

8. In combination, a plurality of trays, each tray having the top and the greater 70 part of one side open, and connections between the trays whereby they may be stacked in superposed relation or extended laterally in stepped relation so that the open tops and sides form one continuous exposure through- 75 out the flight of trays.

9. In combination, a plurality of trays, each tray having the top open and one vertical side open except for a narrow vertically 80 extending strip at this edge of the bottom of the tray, and connections between the trays whereby they may be stacked in superposed relation or extended laterally in stepped relation so that the open tops and sides form one substantially continuous exposure, the strips at the open sides serving 85 to hold articles in place within the trays.

10. In combination, a plurality of trays, each tray having the top open and one vertical side open except for a narrow vertically 90 extending strip at this edge of the bottom of the tray, and connections between the trays whereby they may be stacked in superposed relation or extended laterally in stepped relation so that the open tops and sides form one substantially continuous exposure, and a pad to which samples may be secured resting on the bottom of each tray 95 and held in place between the strip and the opposite vertical side of the tray. 100

11. In combination, a plurality of trays, each tray having the top open and one vertical side open except for a narrow vertically 105 extending strip at this edge of the bottom of the tray, and connections between the trays whereby they may be stacked in superposed relation or extended laterally in stepped relation so that the open tops and sides form one substantially continuous exposure, and a continuous transparent cover 110 for the open top and side of each tray.

12. In combination, a plurality of trays, each tray having the top open and one vertical side open except for a narrow vertically 115 extending strip at this edge of the bottom of the tray, and connections between the trays whereby they may be stacked in superposed relation or extended laterally in stepped relation so that the open tops and sides form one substantially continuous exposure, a pad to which samples may be secured resting on the bottom of each tray and held in place between the strip and the opposite vertical side of the tray, and a continuous transparent cover for the open 120 top and side of each tray. 125

13. A sample-case tray comprising a bottom, ends, and one vertical side, the opposite side and the top of the tray being substantially open, a narrow strip extending ver- 130

tically from the bottom at the open side, and a removable cover for the tray comprising a continuous transparent covering adapted to extend unobstructedly over the open top and 5 side of the tray, and a metallic framework secured to and reinforcing the free edges of the transparent covering, said framework

including a channel strip secured to the lower free edge of the side portion of the covering, and bowed outwardly to yieldably 10 engage behind the vertical strip at the open side of the tray.
